R. E. WEIGEL

TOY BALLOON

Filed May 31, 1927

INVENTOR.
RAYMOND E. WEIGEL

BY *Harry Q. Schneider*
ATTORNEYS.

UNITED STATES PATENT OFFICE.

RAYMOND E. WEIGEL, OF BERKELEY, CALIFORNIA.

TOY BALLOON.

Application filed May 31, 1927. Serial No. 195,195.

The invention forming the subject matter of this application relates to toy balloons.

An object of the invention is to provide a toy made of a plurality of balloons which are connected in such a relation to each other that the air or gas can be transferred from one balloon directly into another.

Another object of the invention is to provide a toy in which a plurality of balloons are connected in such a relation that when the air or gas is transferred from one balloon directly into another balloon a sound is produced.

Another object of the invention is to provide a toy in which a plurality of balloons are connected in such a relation that the air or gas passing out of each balloon produces a different sound.

A further object of the invention is to provide a toy in which a plurality of balloons are connected with each other in such a relation that all of the balloons can be filled with air or gas at the same time.

The above and other objects in view will readily appear as the description proceeds.

Although I have shown and described a preferred embodiment of the invention it is to be understood that changes as to the form, parts and arrangements may be made within the scope of the claims, without departing from the spirit of the invention or sacrificing any of the advantages thereof.

In the accompanying one-sheet of drawing:

Figure 1 is sectional view of the toy balloon,

Figure 2 is a section taken along the line 2-2 of Figure 1.

In carrying out my invention I provide a plurality of balloons 1 having openings 2 thereon, a tubular stem 3 is secured into said openings 2 of the balloons 1 by means of rubber bands 4, but the balloons may be secured to a stem 3 by any other convenient means.

A mouth piece 5 having a passage 6 therein is secured to the stem 3, a one-way intake valve 7 permits the air or gas to pass through the opening 6 into the tubular stem 3, but it does not permit the air or gas to escape through the opening 6. The valve 7 is illustrated as a standard rubber flap valve in use at present on some of the toy balloons. Valves 8 are secured in the end of the tubular stem 3 adjacent to the openings 2 of the balloons 1 and comprise a valve body

9 having an inlet passage 10 and an outlet passage 11 therethrough, an elastic flap valve 12 terminates the inlet passage 10, said flap valve 12 is disposed on the valve body 9 inside 60 of the balloon 1. An exhaust flap valve 13 also made of elastic material terminates the exhaust passage 11 and is disposed on the valve body 9 inside of the tubular stem 3.

The invention operates as follows; the 65 mouth piece 5 is placed on or connected with the source of the air or gas to be blown into the balloons 1. The compressed air or gas opens the valve 7 and passes through the inside of the tubular stem 3 to the inlet passage 10, the pressure of the air or gas stretches the elastic valve 12 at the center portion thereof, thereby separating said center portion from the valve body 9 and permitting the air to pass through this opening 70 into the balloon 1. When the balloon 1 is filled up with air or gas the pressure therein forces the elastic valve 12 against the valve body 9 thereby preventing the escape of the air or gas therefrom. When all 75 of the balloons are partly filled up and the air or gas cannot escape from the balloons, a pressure is exerted on one of the balloons. The increased pressure of the air or gas therein stretches the elastic exhaust 80 valve 13 and the air is forced through the exhaust opening 11 out of the balloon into the tubular stem 3. While the air is forced through the exhaust passage 11 it causes the elastic flap valve 13 to vibrate, the vibration of this elastic valve 13 sets the air 85 in vibration and produces a sound. The air passes through the passage inside of the tubular stem 3 to the inlet passage 10 of the other balloon 1 and forces the elastic 90 intake valve 12 therein to stretch and open sufficiently to permit the air or gas to pass into said balloon. Thus the air or gas is passed from one balloon into the other and every time it opens or closes one of the 95 elastic rubber flap valves the air is set into vibration and the vibration of the air in the passage of the tubular stem 3 produces the sound. The size of the exhaust opening 11 and the stiffness of the elastic valve 100 13 are different at every balloon so that the passing air or gas produces a vibration of a different pitch at every exhaust opening thereby producing a different sound every time when a different balloon is pressed. 105 The combination of this sound of different pitch or quality may be so regulated that in

turn it will imitate some animal or musical sound or tune.

Having thus described my invention what I now claim as novel and desire to secure by Letters Patent is:

1. A toy balloon comprising a tubular stem, a plurality of balloons secured to said stem the opening of each balloon being in registry with the passage in said stem, an intake valve, a plurality of inlet valves, and a plurality of exhaust valves, said inlet and exhaust valves being disposed in pairs in the opposite ends of said stem and in registry with the balloon openings.
- 15 2. A toy balloon comprising a tubular stem, a plurality of balloons secured thereto, each of said balloons having an opening thereon, in registry with the passage in said tubular stem, an intake valve on a mediate portion of the stem, a plurality of vibrating inlet valves, and a plurality of vibrating exhaust valves, said inlet and exhaust valves being disposed in pairs at the opposite ends of said stem and in registry with the balloon opening.
- 20 3. In a toy of the character described a rigid tubular stem, a pair of balloons each having a tubular neck secured to the opposite ends of said stem; a one way intake valve on a mediate portion of said stem, cylindrical valve blocks secured in the opposite ends of said stem, each block having a pair of valves therein, said latter valves opening oppositely to each other, permitting the transfer of air from one balloon to the

other thru said stem when one of the balloons is pressed.

4. In a toy of the character described a rigid tubular stem, a pair of balloons each having a tubular neck secured to the opposite ends of said stem; an annular flange extending at right angles from a mediate portion of said stem, a one way intake valve block secured in said flange and communicating with the inside passage of said tubular stem; cylindrical valve blocks secured in the opposite ends of said stem, each block having a pair of valves therein, said latter valves opening oppositely to each other, permitting the transfer of air from one balloon to the other thru said stem when one of the balloons is pressed.

5. In a toy of the character described a rigid tubular stem, a pair of balloons each having a tubular neck secured to the opposite ends of said stem; an annular flange extending at right angles from a mediate portion of said stem, a one way intake valve block secured in said flange and communicating with the inside passage of said tubular stem; cylindrical valve blocks secured in the opposite ends of said stem, each block having a pair of valves therein, said latter valves opening oppositely to each other, permitting the transfer of air from one balloon to the other thru said stem when one of the balloons is pressed, and being adapted to make a sound when air passes therethru.

In testimony whereof I affix my signature,
RAYMOND E. WEIGEL.
